UNITED STATES PATENT OFFICE

164,660

COVERED CASSEROLE

Eva S. Zeisel, New York, N. Y., assignor to United China and Glass Co., New Orleans, La., a corporation of Louisiana

Application July 12, 1950, Serial No. 11,102

Term of patent 14 years

(Cl. D44—15)

To all whom it may concern:

Be it known that I, Eva S. Zeisel, a citizen of the United States, residing at 431 Riverside Drive, New York, State of New York, have invented a new, original, and ornamental Design for Covered Casserole, of which the following is a specification, reference being had to the accompanying drawing, forming a part hereof.

Fig. 1 is a top view showing my new design of a covered casserole;

Fig. 2 is a side elevation, with parts broken away;

Fig. 3 is an end elevation, with parts broken away.

I claim:

The ornamental design for a covered casserole, as shown.

EVA S. ZEISEL.
